UNITED STATES PATENT OFFICE.

WILLIAM J. SNYDER AND LEVI KNOTT, OF ALTOONA, PENNSYLVANIA.

TOY PISTOL.

1,278,514.

Specification of Letters Patent. Patented Sept. 10, 1918.

Application filed February 11, 1916, Serial No. 77,720. Renewed March 23, 1918. Serial No. 224,389.

To all whom it may concern:

Be it known that we, WILLIAM J. SNYDER and LEVI KNOTT, citizens of the United States, residing at Altoona, in the county of Blair and State of Pennsylvania, have invented certain new and useful Improvements in Toy Pistols, of which the following is a specification.

This invention relates to certain new and 10 useful improvements in toy pistols and the like projecting devices; and as its primary object, it contemplates the provision of a novel device of the above nature that is especially designed to be used for projecting 15 marbles and similar loads and which consists of but few parts whereby it may be cheaply manufactured and easily and quickly dismembered for the purpose of cleaning or repairing.

Another object of the invention is to provide 20 an article of the aforesaid character wherein the body or parent structure may be produced in sections that may be quickly and easily connected so as to insure efficient 25 operation at all times.

A further object is to construct the device in such a manner that the projecting means may be easily and quickly tensioned 30 at the desire of the operator.

A still further object of our invention is to provide a device of the type in question, that is extremely simple in construction, 35 strong and durable, and highly practical from both the standpoint of the manufacturer and the standpoint of the user; and which, it is believed, may be manufactured at a comparatively low cost.

Various other objects and advantages will 40 become apparent during the continuance of the following description.

These objects are accomplished by such means as are shown in their preferred form in the accompanying drawings, described 45 in the following specification and then more specifically pointed out in the appended claims.

In the accompanying drawings wherein like characters designate like parts throughout the several views:

Figure 1 is a view in side elevation showing our invention as in its preferred embodiment.

Fig. 2 is a view in longitudinal section

showing the trigger as in a cocked position 55 and the device otherwise ready for operation.

Fig. 3 is a view in section, taken on the line 3—3 of Fig. 1.

Fig. 4 is a view taken on the line 4—4 60 of Fig. 1.

Fig. 5 is a view in detail of a spring that is used to co-act with the trigger member;

Fig. 6 is a view in section taken on line 6—6 of Fig. 1, and

Fig. 7 is a view in section of a portion, 65 the projecting element showing means whereby the same may be suitably reinforced.

In the present embodiment, we contemplate forming the body or parent structure of substantially complementary sections 10 and 11 respectively, which by reason of their peculiar construction may be primarily stamped from sheet metal. Sections 10 and 70 11 are suitably bent or machined intermediate their ends to provide a housing such as designated in its entirety by the numeral 12, in Fig. 3 and suitably curved adjacent one end to present a substantially circular 75 barrel 13. Said sections are formed at their other end to provide a handle 14; while a connection between the sections adjacent said handle may be obtained by providing the same with inwardly directed bosses 15 80 and 16 respectively, and subsequently connecting said bosses by such means as shown at 17. A connection of this nature will be found very serviceable in connection with the device of my invention as shown in the 85 present embodiment.

The projecting element, such as designated in its entirety by the numeral 18 in Fig. 2 is preferably of rubber or like elastic material and has its respective end portions 95 passed through opposed apertures 19 of the barrel 13 as illustrated. Intermediate its ends, projecting element 18 is suitably enlarged and reinforced such as shown at 20 and 21 in Fig. 7 whereby it may receive a 100 suitable operating member such as will be presently described and fully withstand the wear and tear incident to the repeated actuation of the device. In order to retain the respective end portions of projecting member 18 in position and at the same time provide for the subsequent tensioning and adjustment thereof, suitable means are located on

the barrel 13 which may be constructed as follows.

In carrying the foregoing into effect, barrel 13 has located adjacent its free end a two 5 pronged extension 22 carried by one of the respective body sections and a similar co-acting extension 23 carried by the other body section. Consequently, by bending extensions 22 and 23 oppositely about the barrel 10 as shown in Fig. 6, the ends of the projecting element 18 will not only be held in place but the forward portion of body sections 10 and 11 will also be securely retained against relative movement. Here it is pointed out 15 that apertures 19 are so formed that the gripping of the ends of the projecting element 18 will not tend to cause the premature breaking due to wear of the element on the edges of said apertures.

20 Section 11 is further provided with an inwardly directed boss 24 (as shown in Fig. 3), which serves to pivotally support a setting lever 25 as at 26; the upper end of said setting lever operating through slot 27 of 25 housing 12 and being provided with a finger engaging portion 28. Section 10 on the other hand carries an inwardly directed boss 28 upon which is pivotally mounted a connecting lever 29, as at 30; said connecting 30 lever having a longitudinal slot 31 adjacent one end for reception of stud 32 carried by setting lever 25. The connecting lever is in turn pivotally connected as at 33 with a projecting arm 34 which has its shank portion 35 passed through the enlargement 20 of projecting element 18, as shown in Fig. 2. At its free end, projecting arm 34 carries a head or stop 35 to bear against one face of projecting element 18 and is further provided 40 with a suitable abutment 36 to bear against the other face whereby relative movement is effectually prevented.

45 Section 10 is further provided with an extension 37 which, when bent or turned into the position shown in Figs. 2 and 3, forms a suitable bearing for pivotally supporting a trigger 38 as at 39; trigger 38 operating through a suitable slot 40 whereby it may be conveniently engaged by the finger of the 50 operator. In order to co-act with trigger 38 as shown in Fig. 2, section 11 carries a leaf spring 41 whose free end portion may be passed through suitably disposed apertures 42 in the wall of said section whereby 55 it may be securely retained in place. Consequently, when setting lever 25 is drawn into the position shown in Fig. 2, the lower end thereof is engaged with the upper end of trigger 38, while the projecting element 60 18 is simultaneously moved into a like set position. When the parts are so arranged the marble or other load may be placed in barrel 13 and subsequently projected by element 18 upon proper manipulation of trigger 38.

By reason of the connections hereinbefore mentioned it is obvious that sections 10 and 11 may be quickly and easily assembled or disassembled and that the several parts operating within housing 12 may be removed 70 or replaced for the purpose of substitution or repair.

As shown in Fig. 7, projecting element 18 may be suitably reinforced by the interpolation of strips of fabric or the like adjacent the enlargement 20 so as to prevent premature breaking at this point. The tensioning of the projecting element 18 may be effected by adjusting the ends thereof beneath extensions 22 and 23 so that it will 80 force the marble or other load with the desired velocity at all times.

From the foregoing, it is believed that the advantages and novel features of our invention will be readily understood and, therefore, further detail description is deemed unnecessary.

In reducing our invention to practice, we find that the form referred to herein as the most practical and preferred embodiment is 90 the most efficient, but realizing that certain conditions will necessarily vary in concurrence with the adoption of our device, we desire to emphasize the fact that various minor changes in the details of construction 95 and in the proportion of parts may be resorted to without sacrificing any of the advantages of our invention, as defined in the appended claims.

Having thus fully described our invention, what we claim as new and desire to secure by Letters Patent is:—

1. In a device as aforesaid; body sections forming an intermediate housing, a barrel adjacent one end, a handle adjacent the other, and tongues extending from said sections in overlapping relation, the tongues being bent to engage the sections whereby the sections may be held against relative movement; in combination with a projecting element and 105 means to set and release the same.

2. In a toy pistol; body sections providing a tubular barrel, a projecting element having its ends passed through the wall of said barrel, extensions on one of said sections bent 115 to embrace the opposite section and an extension on said opposite section bent to embrace the first-mentioned section, said sections being positioned to engage and retain the ends of said projecting element; in combination with means to set and release said projecting element.

3. In a toy pistol; body sections providing a tubular barrel, an operating element having its end portions passed through apertures in said barrel, an extension formed on each of said sections bent to embrace the opposite section and to retain the ends of said projecting element; in combination with 120 means including a lever projecting exteriorly 13

of said sections whereby said operating element may be set and a trigger coöperating with said lever.

4. In a toy pistol; body sections providing a tubular barrel and a housing adjacent one end thereof, a projecting element in said barrel having its end portions passed through apertures, an extension on each of said sections bent to embrace the opposite section and retain the ends of said projecting member; in combination with means to set and release said projecting member mounted to be operable in said housing.

5. In a toy pistol; a body formed in sections and providing a housing, a barrel projecting from one end of said housing, a handle associated with the other end, an operating element, means integral with the sections to fixedly secure the ends of said operating element to said barrel and hold the sections against transverse movement, and means operable in said housing to set and release said operating element.

6. In a toy pistol; a barrel, a projecting element having its ends passed through apertures in said barrel to lie exteriorly thereof,

extensions on said barrel to retain the ends of said projecting element, said projecting element being enlarged intermediate its ends, and a housing carrying a handle portion associated with said barrel; in combination with a setting lever rockably mounted in said housing having one end projecting therethrough, a connecting lever pivotally mounted in said housing and including a longitudinal slot, a stud on said setting lever operating in said slot, a projecting arm pivotally connected with said second mentioned lever and having one end passed through the intermediate portion of said projecting element, a trigger having one end projecting exteriorly of said housing to coöperate with said setting lever, and a spring to yieldingly resist movement of said trigger.

In testimony whereof we affix our signatures in presence of two witnesses.

WILLIAM J. SNYDER.
LEVI KNOTT.
